LEADER FORMING MACHINE

Clifford Brignall, Long Beach, Calif.

Application June 20, 1940, Serial No. 341,552

8 Claims. (Cl. 140—102)

This invention relates to a machine for forming leaders for fishing equipment, the general object of the invention being to provide means for forming loops at the ends of each leader with portions of the wire wrapped or coiled closely about the twisted portions which form the shank of the loop.

Another object of the invention is to make the parts adjustable so that leaders of different lengths can be formed and also to make the loops of different lengths.

A further object of the invention is to provide means whereby fish hooks, swivels or other objects can be connected with the looped ends of the leaders while the loops are being formed.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which—

Figure 1 is a top plan view of an apparatus constructed in accordance with the invention.

Figure 2 is a section on the line 2—2 of Figure 1.

Figure 3 is a section on the line 3—3 of Figure 1.

Figure 4 is a section on the line 4—4 of Figure 2.

Figure 5 is a fragmentary plan view showing the means associated with one of the spindles and a portion of the cam carrying shaft.

Figure 6 is a view showing the spindles with the wire extending between the same, the guides and the means for holding objects so that they will be connected with the looped ends of the wire.

Figure 7 is a view partly in section of one of the looped ends of a leader.

Figure 8 is a fragmentary view showing how a swivel is connected with the looped end of a leader while the loop is being formed.

In these views the letter A indicates an upright frame or table having a skeleton top and a shelf 1 resting on an intermediate part of the top and is adapted to be adjusted toward or away from the end 2 of the table top, any suitable means being provided for holding the shelf in adjusted position. A shaft 3 extends longitudinally and slightly above the table top and is jour-

naled to the end parts thereof as shown at 4 and an intermediate part of the shaft is journaled to the shelf 1 as shown at 5, this bearing 5 permitting the shaft 3 to slide through it as the shelf is being adjusted. The shaft carries a pair of cams 6 which have their cam faces facing toward the ends of the table top. A rod 7 extends longitudinally of the table and is adjustably held in a sleeve 8 on the rear end of the shelf 1 and a second rod 7' is adjustably held in a sleeve 8' on the end part 2 of the table. Levers 9 have their rear ends pivotally connected to the adjacent ends of the rods 7 and 7' as shown at 10, the levers extending across the table to a point adjacent the front thereof where said levers have the projections 11 at the front ends. The cams 6 are adjustably connected to the shaft 3 by a screw 12, see Figure 5, and a pin 13 is carried by each lever for engagement by the cam face of the cam as also shown in Figure 5. A pair of supporting plates 14 is slidably arranged on the table top at the front thereof and between the shelf 1 and the end part 2. A pair of rods 15 is pivotally connected with each plate as shown at 16 and the rods of the right hand plate in Figure 1 pass through the horizontally arranged tubular members 17 on the shelf 1 while the rods of the other plate pass through the tubular members 17' on the end part 2. Each of the tubular members is formed with the lubricant receiving means 18 whereby the rods can be lubricated and the ends of each pair of tubular members are connected together as shown at 19 and the outer ends of the rods are connected together by a cross piece 20. A spring 21 connects each cross piece 20 with that cross member 19 which is connected with the inner ends of the pair of tubular members 17 so that these springs tend to move the plates 14 toward each other and thus the plates 14 will be held yieldingly against the projections 11 of the levers 9 but when the front ends of the levers are moved apart by the cams 6 these plates 14 will be moved apart and against the tension of the springs 21. Each plate 14 has a trackway 22 therein which extends transversely of the table top and a small slide or carriage 23 slides in this trackway. A resilient bumper 24 is fastened in the outer end of each trackway and a cable 25 has one end connected to a part of the carriage or slide 23 and the cable passes over a pulley 26 in the outer end of the plate 14 and said cable has a weight 27 attached to its lower end so that this weight acts to hold the carriage or slide 23 in its outward position or in a position engaging the bumper 24. The

carriage is formed with a member 28 which forms a stationary jaw of a clamp, the movable jaw 29 of which is formed on the inner end of a lever 30 pivoted to the carriage as shown at 31 with the jaw forming parts of arcuate shape. A spring 32 connects the outer end of the lever 30 with a stationary rod-like member 33 attached to the carriage and this spring 32 acts to hold the jaw 29 in clamping engagement with the stationary jaw 28 so as to grip one end of a wire W on the carriage. Of course, when the lever 30 is swung away from the member 33 and against the action of the spring 32 the jaw 29 will release the end of the wire.

A bracket 34 depends from the inner end of each plate 14 and an arm 35 is pivoted to the lower end of the bracket and carries a socket 36 at its free end for receiving the lower end of a post 37 which is held in the socket in any suitable manner and a cable 38 is attached to the socket and has a weight 39 at its lower end, this weight acting to hold the arm 35 in a position with its pivoted end engaging a stop 40 and with the post in vertical position. However, these parts are so arranged that the post can be swung in a direction toward the inner end of the plate 14 when desired, it being seen that the arm 35 projects beyond the inner end of the plate 14 so that the post is spaced from said inner end as more clearly shown in Figure 5. The upper end of said post has a slot 41 therein which is in alignment with the gripping face of the jaw 28 so that when a portion of the wire is passed through the slot said wire will extend in a straight line from the post to between the jaws.

A spindle 42 is slidably and rotatably supported by the shelf 1 and a spindle 42' is rotatably supported by the end part 2 but this spindle 42' cannot slide or move longitudinally. The spindle 42 passes through the bearing members 43 and a collar 44 is attached to the spindle between the bearings and a spring 45 has one end bearing against the front bearing and its other end against the collar so as to hold the spindle 42 in a rearward position or in a position where it will be farthest from the spindle 42'. The adjacent ends of the two spindles are formed with needle-like parts 46 which have their ends bent to form hooks 47. The spindle 42 is connected by a chain and sprockets shown generally at 50 to a longitudinally extending shaft 51 rotatably supported on a lower horizontal part A' of the frame. A stub shaft 52 is supported by this part A' and a pinion 53 on the shaft 51 meshes with a gear 54 on the stub shaft while a belt and pulley arrangement 55 connects the stub shaft with the shaft 3 so that the shaft 3 is driven at a different speed from the shaft 51. At the other end of the main frame the shaft 51 has a large pulley 56 attached thereto over which a belt 57 passes which also passes over a small pulley 58 of a motor M supported on a shelf 59 in the frame. The shaft 51 has a gear 60 connected therewith which meshes with a gear 61 on a shaft 62 which also has a sprocket wheel thereon over which a chain 63 passes and which chain passes over a sprocket on the spindle 42'. The gearing is preferably interchangeable so that the spindle 42' can be made to rotate in an opposite direction from the spindle 42 or the two spindles can be made to revolve in the same direction. A push button switch or other type of manually operated switch 64 is provided at the front of the frame for controlling the circuit to the motor M and a mercury switch 65 controls a

circuit to the motor. A cam 66 is arranged on the shaft 3 for controlling the position of the switch 65 and the parts are so arranged that the switch 65 will be moved to close the circuit after the motor has been started by the closing of the switch 64. Then the switch 64 can be released and the circuit to the motor will remain closed by the switch 65 until the cam 66 reaches a certain position when the switch 65 will break the circuit and stop the motor.

A hand lever 67 is pivoted to the bracket 68 on the shelf 1 and said lever when moved to the left in Figure 5 will engage a part 69 on the spindle 42 so as to push the spindle 42 forwardly or toward the other spindle so as to slacken the wire between the spindles.

Each spindle carries a socket forming member 70 for a hook rod 71 which is held in position by a set screw 72. These hook rods are adapted to hold objects, such as the fish hook 73 or the swivel 74 in position to be engaged by the loops to be formed when it is desired to connect the leader with an object.

As shown in Figure 7 this device will form a loop a in each end of the leader wire w with the parts adjacent each loop twisted together as at a' and then the wire is closely wrapped or coiled about the twisted part as shown at a''.

As shown in Figures 1, 5 and 6, one end of the wire W is held between the clamping means 28 and 29 of the carriage on one of the slides or plates 14 with the wire passing through the slot 41 of the post 37 of the plate and then the wire passes over the hook 47 of the spindle 42 and then the wire passes over the hook of the spindle 42' through the slot 41 of the post 37 of the other plate 14 and is then held between the clamping means of said other plate 14. Thus a portion of the wire is stretched between the two spindles with portions adjacent the hooked ends of the spindles passing through the slots of the posts. The weights 27 connected with the carriages or slides 23 hold the wire taut.

The motor is then started by switch 64 which starts to rotate the spindles and said spindles revolve a plurality of times to one revolution of the shaft 3. After the motor has rotated the spindles a few revolutions cam 66 will cause the mercury switch 65 to close the circuit to the motor which keeps the machine operating until the desired number of turns of wire has been wound and the contact is broken automatically as the cam 66 again raises the mercury switch to break the circuit.

The parts are so timed that when the machine stops the pins 13 on levers 9 are at the high parts of the cams 6 so that the plates 14 are adjacent their innermost positions with the posts spaced substantially the length of the twist a'. Then the switch 64 is closed to start the motor which turns the spindles and this results in forming the loops a by twisting the wire as at a'. This also results in turning shaft 3 to place the cams 6 to cause the pins 13 to engage the low parts of the cams and to close switch 65. Then the cams 6 act on the levers 9 to move the plates 14 away from each other and this causes the posts to move slowly along the twists a' so that the wire will be coiled around the twisted parts beginning from that end of the twisted part a' farthest from the loop to the base of the loop. Then the posts 37 are swung toward the plates 14, the arm 35 pivoting on the bracket 34 during this movement so that the post will be spaced from the twisted part of the wire to facil-

itate cutting the wire close to the outer end of the twisted part *a''*. Thus a loop will be formed at each end of the wire with the parts twisted together as shown at *a'* and the twisted part covered by a closely wrapped coil *a''* as shown in Figure 7.

As before stated when a hook, swivel or other object is to be connected to an end of the leader by the loop this object is held in position by the hooked rod *71* placed in the socket *70* as shown in Figures 6 and 8. Of course, the end of this wire to be looped is passed through the eye of the hook or swivel as shown in these figures so that when the loop is formed the object will be held therein. Figure 8 also shows how the wire is wrapped around the twisted part thereof after the twisted part has been formed.

As before stated, this invention is mainly designed for forming loops at the ends of leaders used in fishing equipment but it can be used for other purposes.

The spindles can be made to rotate in opposite directions when the leader is formed of multiple strands of wire so that the strands will be twisted together more tightly but when a single strand of wire is used the gears are changed so as to rotate the two spindles in the same direction and this will avoid kinking the wire.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. In a machine for forming loops in the end of a flexible member, a supporting structure, a pair of spindles rotatably supported in the structure and having hooked ends arranged adjacent each other for having the flexible member looped over the same, slides on the supporting member, springs for moving the slides toward each other, a carriage on each slide, clamping means carried by each carriage for clamping an end of the flexible member, means for yieldingly holding the carriages in an outward position to apply tension to the flexible member, a guide carried by each slide and through which the flexible member passes after passing around the hooks of the spindles, means for rotating the spindles to twist the flexible member adjacent the hooks of the spindles to form loops and means for then moving the slides away from each other to cause the guides to guide the flexible member to cause the spindles to tightly wrap the flexible member around the twisted parts.

2. A device for forming loops in a length of a wire comprising a supporting frame, a pair of spindles rotatably arranged therein and in longitudinal alignment and having hooks at the inner ends for receiving portions of a wire, slides arranged on the supporting member, clamps carried by the slides for clamping the ends of the wire, means for holding the ends of the wire under tension by the clamps, a guide carried by each slide and arranged close to the hooked end of a spindle, means for rotating the spindles to twist the wire adjacent the hooks to form loops and means for then moving the slides away from each other to cause the guides to guide the wire as the spindles are rotated to wrap the wire closely about the twisted parts.

3. A device for forming loops in a length of

- wire comprising a supporting frame, a pair of spindles rotatably arranged therein and in longitudinal alignment and having hooks at their inner ends for receiving portions of a wire, slides arranged on the supporting frame, clamps carried by the slides for clamping the ends of the wire, means for holding the ends of the wire under tension by the clamps, a guide carried by each slide and arranged close to the hooked end of a spindle, means for rotating the spindles to twist the wire adjacent the hooks to form loops and means for then moving the slides away from each other to cause the guides to guide the wire as the spindles are rotated to wrap the wire closely about the twisted parts, holding means on the spindles and supporting means held by said holding means for supporting objects close to the hooked ends of the spindles with parts of the looped wire passing through parts of the objects.
- 20 4. A device for forming loops in a length of wire comprising a supporting frame, a pair of spindles rotatably arranged therein and in longitudinal alignment and having hooks at their inner ends for receiving portions of a wire, slides arranged on the supporting member, clamps carried by the slides for clamping the ends of the wire, means for holding the ends of the wire under tension by the clamps, a guide carried by each slide and arranged close to the hooked end of a spindle, means for rotating the spindles to twist the wire adjacent the hooks to form loops and means for then moving the slides away from each other to cause the guides to guide the wire as the spindles are rotated to wrap the wire closely about the twisted parts, and manually operated means for moving one spindle toward the other to release the looped wire from the spindles.
- 25 5. A device for forming loops in a length of a wire comprising a supporting frame, a pair of spindles rotatably arranged therein and in longitudinal alignment and having hooks at the inner ends for receiving portions of a wire, slides arranged on the supporting frame, clamps carried by the slides for clamping the ends of the wire, means for holding the ends of the wire under tension by the clamps, a guide carried by each slide and arranged close to the hooked end of a spindle, means for rotating the spindles to twist the wire adjacent the hooks to form loops and means for then moving the slides away from each other to cause the guides to guide the wire as the spindles are rotated to wrap the wire closely about the twisted parts, and means for adjusting one spindle and its slide relative to the other spindle and its slide for adjusting the length of the wire having the loops formed at its ends.
- 30 6. A device for forming loops in a length of a wire comprising a supporting frame, a pair of spindles rotatably arranged therein and in longitudinal alignment and having hooks at the inner ends for receiving portions of a wire, slides arranged on the supporting frame, clamps carried by the slides for clamping the ends of the wire, means for holding the ends of the wire under tension by the clamps, a guide carried by each slide and arranged close to the hooked end of a spindle, means for rotating the spindles to twist the wire adjacent the hooks to form loops and means for then moving the slides away from each other to cause the guides to guide the wire as the spindles are rotated to wrap the wire closely about the twisted parts, and means for adjusting the throw of the means for moving the
- 35 70 75

slides to adjust the size of the loops at the ends of the wire.

7. A device for forming a loop in an end of a flexible member comprising a supporting structure, means therein for holding one end of the flexible member, a spindle rotatably supported in the structure and having a hook at one end over which a portion of the flexible member passes, a slide on the supporting structure adjacent the hooked end of the spindle, a clamp on the slide for engaging an end of the flexible member, means for holding the flexible member under tension by the clamp, a guide carried by the slide and arranged close to the hooked end of the spindle, means for rotating the spindle to twist the flexible member adjacent the hook to form a loop and means for then moving the slide to cause the guide to guide the flexible member as the spindle is being rotated to wrap the flexible member closely about the twisted parts.

8. A device for forming a loop in an end of a flexible member comprising a supporting structure, means therein for holding one end of the

flexible member, a spindle rotatably supported in the structure and having a hook at one end over which a portion of the flexible member passes, a slide on the supporting structure adjacent the hooked end of the spindle, a clamp on the slide for engaging an end of the flexible member, means for holding the flexible member under tension by the clamp, a guide carried by the slide and arranged close to the hooked end of the spindle, means for rotating the spindle to twist the flexible member adjacent the hook to form a loop and means for then moving the slide to cause the guide to guide the flexible member as the spindle is being rotated to wrap the flexible member closely about the twisted parts, said guide comprising a post having a slot in its upper end through which the flexible member passes, and means for pivoting the post to the slide to permit the post to be swung away from the spindle to permit the flexible member to be cut between the post and the spindle.

CLIFFORD BRIGNALL.
